UNITED STATES PATENT OFFICE.

WILLIAM J. BUSSINGER, OF PHILADELPHIA, PENNSYLVANIA, ASSIGNOR TO THOMAS DEVLIN AND LOUIS J. MCGRATH, COPARTNERS TRADING AS THOMAS DEVLIN & COMPANY, OF PHILADELPHIA, PENNSYLVANIA.

QUICK RETURN FOR FEEDING DEVICES.

SPECIFICATION forming part of Letters Patent No. 708,863, dated September 9, 1902.

Application filed November 4, 1901. Serial No. 81,042. (No model.)

To all whom it may concern:

Be it known that I, WILLIAM J. BUSSINGER, a citizen of the United States, residing in the city and county of Philadelphia, State of Pennsylvania, have invented a new and useful Improvement in Quick Returns for Feeding Devices, of which the following is a specification.

My invention consists of an improvement in a quick return for feeding devices, wherein means are provided for releasing the said feeding device, whereby the same can be raised or lowered by hand.

It further consists of novel details of construction, all as will be hereinafter set forth.

Figure 1 represents a side elevation of a machine having a quick return embodying my invention attached thereto. Fig. 2 represents a sectional view on line $x-x$, Fig. 1, 20 showing a side elevation of the same. Fig. 3 represents a sectional view of the upper portion of Fig. 2, showing the stem in section. Figs. 4 and 5 represent plan and sectional views of the quick return, showing the parts 25 in different positions. Fig. 6 represents a side elevation of the quick return in position on an enlarged scale. Fig. 7 represents a side elevation of a slightly-different form of quick-return device. Fig. 8 represents a sectional view on line $y-y$, Fig. 1. Fig. 9 represents a side elevation of a portion of the device in detached position.

Similar letters of reference indicate corresponding parts in the figures.

Referring to the drawings, A designates a machine which is adapted to be used for pressing material—such as sausage, &c.—and which forms no part of my invention, but I have shown the same in order to illustrate 35 my invention as applied thereto; but I do not desire to be limited to any form of machine, since my device is applicable to others. In the machine as illustrated the essential features consist of a base B, having standards C arising therefrom and supporting a yoke or casting D, the base being adapted 40 to support a receptacle E, having a suitable outlet F.

G designates a plunger adapted to move in 45 the receptacle and fit the same, which plunger

is carried by the threaded stem H, which passes through suitable collars in the yoke D, which latter is provided with a key J, which enters the slot K in the stem H, whereby the latter is prevented from turning, but can 55 move up and down in said yoke.

L designates a crank connected with the shaft M, which is suitably journaled in the yoke D and is provided with a gear N.

P designates a sleeve which is adapted to 60 rest upon a suitable portion of the yoke D around the stem H and has a cut-away portion in which is adapted to fit the portion or plate Q, which is preferably curved to correspond to the shape of the sleeve P, and on 65 the interior face of said portion are screw-threads R, and on the exterior is situated a lug or projection S, said sleeve being provided with a gear T, which is adapted to mesh with the gear N when the parts are 70 in the proper position, it being noticed that the plate or portion Q is not connected with the sleeve P, but moves freely with respect to the same and is held in position by means of a collar formed by the jaws U and V, which 75 are pivoted together at W, one of said jaws U being connected with or forming part of a yoke A', which engages with a portion of the frame of the machine and to which is pivoted a lever B', having a nose C' thereon, said lever 80 having an arm D' movably connected therewith and which is guided between the ways E' on the yoke A', said arm having a cut-away portion or slot F', through which is adapted to pass at the proper time a lug or projection 85 G', which is mounted on the jaw V. A spring H' is secured to the yoke A' and bears against the jaw V, which is the movable jaw, to hold the same in a normally closed position. The handle J' is secured to the stem H for the 90 proper manipulation thereof.

The operation is as follows: In describing the invention I will first describe the operation of the machine as illustrated, although the same, as before mentioned, forms no part 95 of the present invention, but illustrates one method of applying the invention. The material to be pressed is placed in the receptacle E, the plunger G being first raised for the proper manipulation of the crank L'. The 100

plunger is caused to descend into the receptacle and press the material, this being accomplished by means of the gear N, meshing with the gear T, mounted on the sleeve P, 5 which is caused to revolve and carry with it the plate Q, the screw-threads R of which being in engagement with the screw-threads on the stem H, the parts being in the position seen in Fig. 4. When the plunger G has 10 descended into the receptacle as far as it is desired and the operator wishes to return the plunger to its elevated position, the lever B' is moved so that the nose C' thereon is in the path of the revolution of the lug S, so by reversing the revolution of the crank L the 15 parts are moved in the opposite direction from that in which they had been previously moving and the lug S engages with the shoulder C' and is held thereby, so that as the 20 crank is turned the jaws V and U are separated, the jaw V being forced out by the plate Q, the parts assuming the position seen in Fig. 5, it being seen that the screw-threads R are thus disengaged from the threads on 25 the stem H, which latter therefore can be quickly lifted by the operator taking hold of the handle J' and elevating the same. It will be noticed that when the lever B' is moved over it carries with it the arm D', so that the 30 lug G' will pass through the slot F' in said arm D', and that when the parts are in the position seen in Fig. 4 the jaw V is locked in position, since the lug G' bears against the arm D' and is prevented from moving over 35 thereby until the lever B' is moved, which carries with it the arm D' and causes the slot to be situated in the line of movement of said lug G', as above stated. After the flange and stem have been raised or adjusted to the desired 40 position, the parts being in the position seen in Fig. 5, it will be noted that by turning the crank in order to operate the parts in the opposite direction from that indicated by the arrow in the said Fig. 5 the projection 45 S will be removed from the shoulder C', so that the pressure thereon is relieved and likewise on the jaw V. The spring H' then acts to throw back the jaw V, and with it the plate Q, so that the screw-threads thereof engage 50 again with the threads of the stem H'. The arm B', however, remains in the same position as is seen in Fig. 5, but by continuing the movement of the crank and the revolution of the sleeve P and plate Q in the reversed 55 direction, as indicated by the arrow in Fig. 5, the lug S contacts with the arm B' and returns it to the position seen in Fig. 4, whereby the jaw V is locked in position, as before stated.

60 In Figs. 7, 8, and 9 I have shown a slightly modified or different construction from that already described, in which I employ a body portion J'', which is suitably secured to a proper portion of the frame of the machine 65 and which carries a spring-actuated finger or dog K', which latter is adapted to bear against the outer surface of the sleeve L', which sur-

rounds the stem M', said sleeve carrying a key N', which fits into a suitable opening in said sleeve and is held therein by means of 70 the spring P', which can be of any desired shape, said key having the opening Q' and the extending portion R', which is adapted to move with the key N' and sleeve L' in the path of the finger K', it being seen that the 75 key N' is provided with screw-threads on its inner face, which is adapted to engage with the threads on the stem M'. When the sleeve L' is rotated in the direction indicated by the arrow, the projecting portion R' will 80 strike the finger K' and throw it back, so that the sleeve can turn, and the stem M' will be lowered, together with the plunger on the end thereof. When, however, the sleeve is rotated in the opposite direction from that 85 indicated by the arrow, the finger L' will enter the opening Q' and force out the key N', so that the screw-threads thereon will be disengaged from the threads on the stem M' and the latter can be raised and lowered, as 90 desired.

It will be apparent that slight changes may be made by those skilled in the art which will come within the scope of my invention, and I do not, therefore, desire to be limited 95 in every instance to the exact construction herein shown and described.

Having thus described my invention, what I claim as new, and desire to secure by Letters Patent, is—

1. In a quick return for feeding devices, a threaded stem, a sleeve surrounding the same, a plate having threads on its inner face adapted to engage with and be disengaged from the threads on said stem and a collar for holding 105 said plate in position and which is operated when said plate is disengaged from the stem and means for revolving said sleeve and plate whereby the stem can be raised and lowered.

2. In a quick return for feeding devices, a stem, a sleeve surrounding the same, means for revolving said sleeve, a plate having threads on its inner face adapted to engage with the threads on said stem, a lug on said plate, and 115 means engaging with said lug for moving said lug whereby said threads are engaged with or disengaged from said stem.

3. In a quick return for feeding devices, a threaded stem, a sleeve surrounding the same, 120 a plate having threads on its inner face adapted to engage with said stem, means for raising and lowering said stem, means for operating said plate whereby the same engages with or is disengaged from said stem, and 125 means on said plate which is normally disengaged from said operating means, and is engaged thereby to operate said plate.

4. In a quick return for feeding devices, a stem, a sleeve surrounding the same, means 130 for revolving said sleeve and plate, a cut-away portion in said sleeve, a plate adapted to fit said cut-away portion and having threads on its inner face, a collar adapted to normally hold said

plate in position, and means for operating said plate for moving said threads from the threads on said stem whereby the latter can be quickly raised or lowered.

5 5. In a quick return for feeding devices, a stem, a sleeve having a movable threaded portion, means for revolving said sleeve and threaded portion, pivoted jaws engaging said threaded portion whereby the same is moved from engagement with said stem.

10 6. In a quick return for feeding devices, a sleeve, an interiorly-threaded portion acting therewith, a gear on said sleeve, a lug on said threaded portion, spring-actuated jaws for holding said parts in normal position, a lever adapted to engage said threaded portion whereby the threads thereof are disengaged from the stem and the latter can be raised or lowered as desired.

15 7. In a quick return for feeding devices, a stem, a sleeve, a threaded portion movably connected therewith, jaws pivoted to each other and normally holding said sleeve and threaded portion together, a gear on said sleeve adapted to be operated to turn the latter whereby the same is raised and lowered, a lever adapted to engage with said threaded portion and cause the same to open said jaws whereby said threads on said portion are moved from engagement with the stem and the latter can be raised and lowered.

20 8. In a quick return for feeding devices, a stationary jaw, a spring-actuated jaw pivoted thereto, a lever pivoted to said stationary jaw, an arm having a slot therein connected with said lever, a lug on said movable jaw adapted to abut against said arm when the latter is in certain positions and adapted to pass through said slot at the proper time,

a threaded stem, a sleeve surrounding said stem and having a gear thereon, and a plate having threads adapted to engage with the threads on said stem, said jaws holding said sleeve and plate and said lever being adapted to engage with said plate.

25 9. In a quick return for feeding devices, a stem, a sleeve surrounding the same, a plate having threads adapted to engage with the threads on said stem, means for revolving said sleeve and plate for raising and lowering said stem, a lug on said plate and means engaging with said lug for moving said plate, whereby said threads are engaged with or disengaged from said stem, and means for locking said plate in either position.

30 10. In a quick return for feeding devices, a sleeve, an interiorly-threaded portion acting therewith, a gear on said sleeve, a lug on said threaded portion, means for holding said parts in normal position, and a lever adapted to engage with said threaded portion, whereby the threads thereof are disengaged from the stem and the latter can be raised or lowered as desired.

35 11. In a quick return for feeding devices, a stem, a sleeve, an interiorly-threaded portion acting therewith, means for revolving said sleeve and threaded portion, and means normally out of the path of the movement of said threaded portion but which is adapted to be operated to engage therewith in order to remove the threads from the threads of the stem, whereby the latter can be raised or lowered.
